ALBERT E. BERDON, OF EAST ORANGE, NEW JERSEY

CLOTHES RACK

Application filed December 2, 1929. Serial No. 410,992.

The objects of this invention are to provide a rack suitable for drying clothes in "apartments" and like places where space is limited, which will afford a maximum of drying facilities with a minimum of weight and size, which will be foldable in a small space when not in use, easily portable, set up and taken down, which will be inexpensive and of a nature not to detract from its surroundings and which will be thoroughly practical and efficient.

These objects are attained by certain novel features of construction, combination and relation of parts as hereinafter pointed out and broadly covered in the claims.

The drawings accompanying and forming part of this specification illustrate two of the many possible commercial embodiments of the invention, it being understood that the exact form may vary without departure from the true spirit and scope of the invention.

Fig. 1 is a broken perspective view illustrating the rack as set up and in use; Fig. 2 is an enlarged broken side elevation of the rack; Fig. 3 is a bottom plan view of the rack in folded condition; Fig. 4 is an end view illustrating the rack in its position of use; Fig. 5 is a broken part sectional detail illustrating the end fastening of one of the clothes supporting rods or wires; Fig. 6 is a broken part sectional end view showing a modified form of the invention. Fig. 7 is a broken perspective view of this second form of the rack.

One of the important practical features of the invention is the construction and arrangement of the rack in such a way that it may be combined with a bath tub utilizing the latter as a base or support for the rack and as a drain to catch the drip from the clothes. This novel combination furthermore, locates the rack with its clothes in such a position that it is out of the way and actually can be hidden from sight by drawing the curtains with which the tub is usually equipped.

The particular combination described is illustrated in Fig. 1, where the rack is indicated generally at 7 supported in elevated relation over the tub 8 and of a size and shape to be accommodated within the enclosure of the bath curtains 9.

In the detail views, it will be seen that the

rack shown in the present disclosure is made up of a light generally rectangular frame 10 of angle iron, arranged with the two flanges at the top and at the inside of the frame, with rods or wires 11 spaced in convenient relation and extending longitudinally between the vertical end flanges of the frame. These rods or wires or other clothes supporting elements or element, may be secured in any suitable way. At present, it is preferred to use separate lengths of relatively stiff wire, each length flattened or headed at one end at 12 to shoulder against one end flange and threaded at the opposite end at 13 to receive a nut 14 bearing against the opposite end flange. This construction is cheap but particularly efficient and desirable, because the rods can be quickly engaged in the frame, the laterally extending lugs 12 hold the rods against turning while the nuts are being tightened up. These nuts enable a desired degree of tension being exerted to hold the wires tight against rattling and the construction permits of any broken rods being quickly and easily replaced at any time.

To utilize the tub as the support, the frame of the rack is equipped with suitable posts or lugs designed to cooperate with the tub structure and preferably arranged to fold in flat relation to the frame when not in service.

In the form of the invention shown in Figs. 1 to 4, the supports are of generally U-shape consisting of the side pieces 15 pivoted at their upper ends to the side flanges of the frame at 16 and connected at their lower ends by transversely extending reaches 17. These latter are shown as adjustably connected by clamps in the form of C-shaped clips 18 surrounding overlapped portions of the same and secured by set screws 19. As particularly shown in Fig. 4, this adjustable connection enables the dependent supports of the frame to be spread or approached more or less to fit them to different widths of tubs.

At the lower ends, the supporting members 15 are shouldered or otherwise suitably shaped or constructed as indicated at 20 to fit or properly cooperate with the rim of the tub, and to prevent scratching, these rim en-

gaging portions may be protected as by means of sleeves 21 of rubber tubing or the like. The upright supports 15 may be initially given a slight outward bow as indicated in Fig. 4, providing a certain degree of outward spring to yieldingly grip the tub. This facilitates the setting of the clamps to hold the members where they will best fit the tub and because of these members to remain engaged with the tub if the clamps should accidentally come loose.

To hold the supporting legs in both operative and inoperative relation, special spring clamps are provided in the present disclosure in the form of spring plates 22 secured over the outer faces of the members 15 by the pivot rivets 16, said plates having inbent flanges 23 positioned to serve as stops limiting the downward swinging movements of the supports to the upright position shown in Fig. 2 and provided opposite said flanges with inbent vertical shoulders 24 and horizontal shoulders 25. The two rectangularly related shoulders 24 and 25 are shown as provided by indenting the corner portions 26 of the plates on the rectangular lines described, thus enabling shoulders 24 to yieldingly hold the supports in the upright relation and shoulders 25 to yieldingly retain the supports in the folded position indicated by the dotted lines. These plates are sufficiently springy to yield as the legs are swung from one position to the other, the inwardly struck portions 26 serving as inwardly extending stop lugs or cams cooperating with the edges of the supporting legs.

The spring plates are also shown in Fig. 2 as approximating or bearing against the undersides of the horizontal flanges of the frame, so that said holding plates can not turn with the swinging movements of the lugs. The inturned stop flanges 23 at the outer edges of the plates may extend across the ends of the plates as indicated, so as to reinforce and "stiffen" the plates to an extent, saving them against permanent distortion when they are "sprung" out of the flat plane by the shifting of the lugs from one position to the other. These lugs as indicated may be made of ordinary flat strip material and all the parts may be suitably rust-proofed or be made of rust-proof material.

The device is quickly set up for use by simply swinging the legs downwardly to the upstanding position and then placing the rack over the tub with the curved feet 20 resting on the rim of the tub. In this condition, the tub forms a part of the base or support for the rack, the combined height of tub and the rack legs serving to hold the clothes supporting members at such a height that the clothes will hang free of the bottom of the tub. In addition to its function then as a support, the tub serves as a catch or

drain for the drip from the clothes. The rack frame preferably does not extend out appreciably beyond the outlines of the tub and consequently the curtains may be drawn to entirely conceal the rack and the "wash" which it supports. 70

It will be clear from the foregoing that the invention resides largely in the combination of the special rack and tub and the curtain for hiding and protecting the rack with its wash supported in the tub. It will be evident also that the particular form of the rack may vary still within the scope of this invention, for example, as indicated in Figs. 6 and 7, where the rack is designed to be supported in an inclined relation on the tub by means of short dependent supports 27 at the lower corners of the frame engaging one side edge of the tub and the longer folding supporting lugs 28 in the nature of the U-shaped frame 29 pivoted at its upper ends at 30 to the rack frame and shouldered as at 31 to engage the opposite rim portion of the tub. 76

This second form of the invention, the same as the first, can be folded into small space and stowed away behind a door or in a closet and when required for use can be quickly set up on the tub and be concealed by the tub curtains. 90

As shown in Fig. 1, the guards on the legs of the rack may be of split construction, so as to be engaged the more readily over the shouldered feet portions of the legs. This view also shows how clothing, such as stockings, may be suspended full length, as by catching them on the rods or lines by means of ordinary clothes pins. 100

What is claimed is:

1. A clothes drier, comprising a rack of a size to fit over a bath tub and carrying "lines" for hanging drying clothes, said rack being provided with feet for supporting the same in elevated position above a bath tub, said feet being collapsible to enable storing of the rack incompactly folded relation when not in actual service, said folding supporting structure including dependent legs hinged to the body of the rack and foldable thereagainst and overlying spring clips secured over the pivoted portions of the legs and having stop lugs for retaining the legs in their various positions of adjustment. 110

2. A clothes rack, comprising a frame, supporting legs pivoted thereto, spring plates overlying the pivoted portions of said legs and having inturned stop flanges and opposed to said stop flanges indented leg portions, said stop flanges and leg portions engaging over opposite edges of the legs to yieldingly retain the same in position. 120

3. A clothes rack, comprising an angle iron frame provided with clothes hanging elements and arranged with the flanges of said frame uppermost and innermost, a support 125

ing leg and a pivot member securing said leg in pivoted relation to said inner flange of the frame, a spring retaining plate secured by said pivot member in position overlying the leg, said plate having engagement beneath the upper flange of the frame to limit rotative movement of the same and being provided with an inwardly struck lug portion engageable with different portions of the leg to 5 yieldingly retain the same swung into folded relation against the frame or into extended 10 position for supporting the frame.

4. A clothes rack, comprising an angle iron frame provided with clothes hanging 15 elements and arranged with the flanges of said frame uppermost and innermost, a supporting leg and a pivot member securing said leg in pivoted relation to said inner flange of the frame, a spring retaining plate secured by 20 said pivot member in position overlying the leg, said plate having engagement beneath the upper flange of the frame to limit rotative movement of the same and being provided with an inwardly struck lug portion 25 engageable with different portions of the leg to yieldingly retain the same swung into folded relation against the frame or into extended position for supporting the frame, said spring plate furthermore having an 30 inturned flange in opposition to said inwardly struck lug portion stiffening the plate against permanent distortion from the 35 springing of the same by the leg movement aforesaid.

5. A clothes rack, comprising a frame of light angle iron, arranged with the flanges of the same horizontal and vertical and with the vertical flanges at the inside of the frame and the horizontal flanges at the top of the 40 frame projecting outwardly beyond the vertical flanges, supporting members pivoted to the vertical flanges beneath the outstanding portions of the horizontal flanges and clothes supporting elements strung across 45 the frame between the vertical flanges with their outer ends protected beneath the outstanding portions of the horizontal flanges.

6. A clothes rack, comprising a frame of light angle iron having vertical and horizontal flanges, clothes supporting wires extending across the frame and engaged in the vertical end flanges of the frame, said wires having laterally struck lugs forming anti-turning shoulders engageable with the 50 flanges and screw threaded ends for receiving nuts engageable with the flanges to tighten the wires in the frame.

7. A clothes rack, comprising a continuous one-piece light angle iron frame having the 60 flanges of the same disposed vertically and horizontally, the vertically disposed flanges having openings therein at the ends of the same, clothes supporting wires engaged in said openings and each having a head at one 65 end for engagement with the vertical flange

at such end and a screw-threaded opposite end, nuts engaged on the screw-threaded ends of the wires and adapted to be tightened against the vertical flange at such end of the frame for holding the wires taut and the 70 frame braced in compression and U-shaped supports hinged at their ends to the vertical flanges of the frame and having the loop portions of the same indented to fit over the 75 rim of a bath tub and spring means for resiliently holding said U-shaped supports folded up beneath the frame or rigidly extended for cooperative engagement with a bath tub structure.

8. A clothes rack, comprising a light rigid frame, clothes supporting lines carried by said frame, U-shaped supports pivoted at their ends to said frame and having between such ends connecting reaches extensible and contractable to fit different widths of bath 80 tubs and means for adjustably retaining said 85 extensible and contractable reaches in adjusted relation for proper engagement with tubs of different widths.

9. A clothes rack, comprising a light angle iron frame provided with means for supporting the same in a generally horizontal relation, said frame in such relation having the flanges of the same disposed horizontally and vertically, with the horizontal flanges at the top of the frame and the vertical flanges below the horizontal flanges and at the inside of the frame, the supporting means for the same being pivoted to the vertical flanges in position beneath and covered by the overstanding portions of the horizontal flanges and clothes supporting lines engaged with the vertical flanges having end securing abutments disposed beneath and covered by the 95 horizontal outstanding flanges.

In testimony whereof I affix my signature.
ALBERT E. BERDON.
